ATTORNEYS.

UNITED STATES PATENT OFFICE.

FRANK P. DWYER, OF PHILADELPHIA, PENNSYLVANIA, ASSIGNOR TO TRAVELIGHT MFG. CO., OF PHILADELPHIA, PENNSYLVANIA, A CORPORATION OF DELAWARE.

SATCHEL OR THE LIKE.

1,370,636.

Specification of Letters Patent. Patented Mar. 8, 1921.

Application filed August 23, 1920. Serial No. 405,394.

To all whom it may concern:

Be it known that I, FRANK P. DWYER, a citizen of the United States, residing at Philadelphia, county of Philadelphia, State 5 of Pennsylvania, have invented a new and useful Satchel or the like, of which the following is a specification.

My invention consists of a school or other satchel formed of members adapting the 10 same to be swung on the shoulders or back of a child or to be converted into a hand-carrying bag or into a knapsack at will, the construction of the parts and operation of the same being hereinafter described and the 15 novel features of the device pointed out in the claims that follow the specification.

The invention is satisfactorily illustrated in the accompanying drawing but the important instrumentalities thereof may be 20 varied, and so it is to be understood that the invention is not limited to the specific details shown and described, as long as they are within the spirit or scope of the claims.

Figure 1 represents a perspective view of 25 a school satchel embodying my invention.

Fig. 2 represents a rear elevation of a portion thereof.

Figs. 3 and 4 represent perspective views 30 of opposite faces of the device converted into a carrying bag.

Fig. 5 represents a perspective view of the device converted into a knapsack.

Fig. 6 represents a bottom plan view of a 35 detached portion.

Similar numerals of reference indicate corresponding parts in the figures.

Referring to the drawing—

1 designates a satchel consisting of the body 2, the covering flap 3, the two-part 40 shoulder strap 4, the buckle 5 on said strap for adjusting the length of the latter, the snap hooks 6 on the terminals of the sections of said strap, the auxiliary loops or rings 7 of metal or other suitable material 45 on the back of the body 2 for connection of the snap hooks therewith, the leather or other straps 8 on the flap 3 and the buckles 9 on the body 2, said buckles 9 and straps 8 being adapted to retain the flap in closed 50 condition, the members thus far described forming a school satchel of conventional form.

The upper ends of the straps 8 are formed into or with bends 10 with which are con-

nected the auxiliary loops or rings 11 of 55 metal or other suitable material which loops in the present case are disposed on the front face of the flap 3 so as to be conveniently accessible.

On the bottom of the body is the auxiliary 60 loop or ring 12 of metal or other suitable material which is connected therewith by the strap 13, the latter being secured to said bottom by rivets 14 or other suitable means.

The body 2 has on the outer face the 65 pocket or wallet-like member 15 for well known purposes.

It will be seen that the strap 4 may have its snap hooks connected with one of the front loops 11 and one of the rear loops 7 70 and its intermediate portion reeved through the other front loop 11 and the other rear loop 7 and doubled on itself, as in Fig. 3, forming a double grip for carrying the satchel after the manner of a hand-bag, as 75 shown in Figs. 3 and 4. It will be noticed that the loops 11 are on the flap 3 and the loops 7 are on the back 2 at about coincident places so that when the strap 4 is reeved through certain of said loops and connected 80 by the snap hooks with the other loops, said strap forms a double grip as of a hand bag for carrying the latter uniform from both lengths of the strap.

Again the snap hooks of both terminals of 85 the strap 4 may be connected with the rear loops 7 and its intermediate portion reeved through the bottom loop 12 forming the strap into opposite loop portions 16 for the insertion of the arms therewith so 90 that the satchel is converted into a knapsack and may be carried as such on the back of the wearer, it being seen that by the auxiliary members on the body as named and the manipulation of the strap 4, a satchel, 95 a carrying bag, and a knapsack may be interchangeably formed and the conversion of one of said features to one of the others may be readily effected and without adding material expense or weight to the original feature of a school satchel or bag and without requiring much service to accomplish the result.

Of course, I do not limit myself to a school satchel or bag for carrying books as it 105 may be used for tools or other articles without departing from my object.

Having thus described my invention, what

I claim as new and desire to secure by Letters Patent, is:

1. A convertible satchel of the character described consisting of a body having thereon a closing flap, ring-like members on the back of said body, ring-like members on the front of said flap, a detachable carrying strap, and connecting devices on the terminals of said strap detachable from said ring-like members adapting the strap to be engaged with either ring-like member on said back, and either ring-like member of said flap and reeved through the other ring-like members of said back and flap adapted to form a double-carrying grip device for the satchel.
2. A convertible satchel of the character stated, consisting of a body, a carrying strap

therefor, loop-like members on the back of the body, means on said strap adapted to 20 removably connect it with said members for carrying said satchel as a school satchel, auxiliary loop-like members on the front of the body with which the ends and intermediate portions of said strap may engage and 25 form a doubled handle for said body converting the device into a hand carrying bag, and an auxiliary loop-like member on the bottom of the body with which the intermediate portion of said strap may engage, 30 converting the device into a knapsack each feature being at will.

FRANK P. DWYER.
